UNITED STATES PATENT OFFICE.

CLAUDE H. POLK, OF ANACONDA, MONTANA.

LOADING APPARATUS FOR POWDERED MATERIALS AND THE LIKE.

1,211,348.

Specification of Letters Patent.

Patented Jan. 2, 1917.

Application filed February 7, 1916. Serial No. 76,785.

To all whom it may concern:

Be it known that I, CLAUDE H. POLK, a citizen of the United States, residing at Anaconda, in the county of Deerlodge and State of Montana, have invented new and useful Improvements in Loading Apparatus for Powdered Materials and the like, of which the following is a specification.

This invention relates to improvements 10 in loading devices for powdered material such as calcine and the like.

In carrying out the present invention, it is my purpose to provide a loading device of the class described whereby the powdered material may be discharged into the cars and the dust incident to such discharge conveyed away from the place of loading so as to eliminate the inconveniences heretofore incident to the loading of powdered 20 material.

It is also my purpose to provide loading apparatus for calcine, etc., wherein the dust guards will be normally elevated so that the cars may be readily moved into position below the hoppers and wherein the controlling valve of the hopper may be opened, the dust guard lowered and the valve controlling the dust flue opened simultaneously by a single operation, thereby enabling the 30 apparatus to be brought into service and rendered inactive quickly and conveniently.

With the above and other objects in view, the invention consists in the construction, combination and arrangement of parts 35 hereinafter set forth in and falling within the scope of the claims.

In the accompanying drawings: Figure 1 is a view in side elevation showing two loaders arranged side by side over a trackway 40 and the cars beneath the loaders. Fig. 2 is an end elevation of one of the loaders. Fig. 3 is a vertical sectional view through the same. Fig. 4 is a horizontal sectional view therethrough. Fig. 5 is a bottom plan view 45 of one of the loaders. Fig. 6 is a view in side elevation showing a modified form of loader.

Referring now to the drawings in detail, A, A designate loaders arranged side by side above the trackway and spaced apart longitudinally of the trackway. The loaders A, A are identical in construction and each embodies a hopper 1 adapted to contain calcine or other powdered material and having the upper end open to receive such material. 55 The lower end of the hopper 1 is formed

with a short discharge spout 2 and surrounding the spout 2 and capable of sliding movement thereon is a ring 3 having the upper edge flared outwardly to conform to the shape of the lower end of the hopper. 60 Surrounding the lower portion of the ring 3 and suitably secured thereto is the upper end of a truncated cone-shaped hood 4, while secured to the lower end of the hood 4 is a dust guard 5 formed centrally with an opening 6 registering with the hood 4 and the spout 2. In the present instance, the dust guard is substantially rectangular in outline to fit over the top of the car and formed on the edges of the dust guard are depending flanges 7 adapted to overlap the sides and ends of the car. 65

Formed in the guard 5 adjacent to one side thereof is an outlet opening 8 and secured to the upper surface of the guard in 70 alinement with the opening 8 is a pipe section 9, while telescoping over the upper end of the pipe section 9 is the lower end of an outlet pipe 10 and the outlet pipes 10 of the adjacent loaders open into a common outlet 75 flue 11.

Mounted in the outlet pipes 10 is a damper 12 and secured to one end of the shaft of the damper is an arm 13, while connecting the arm 13 with the dust guard 5 is a 80 rod 14.

Formed in one side of the hopper 1 at the spout end thereof is an opening 15 and slideable across the outlet end of the hopper is a controlling valve 16 movable through the 85 opening 15 and connected with the end of the valve 16 that projects through the opening 15 is one end of an arm 17.

Formed on the guard 5 at opposite sides of the hood 4 are pairs of ears 18 and the 90 ears upon each side of the hood are spaced apart transversely of the guard, as clearly illustrated in Fig. 1 of the drawings. Pivotaly connected with the respective pairs of ears are the lower ends of links 19 and the 95 upper ends of the links at each side of the hood are pivotally connected to each other and to one end of an arm 20. The other ends of the arms 20 are fixed to a shaft 21 journaled in horizontally alining bearings 100 22 carried by the adjacent side of the hopper 1 and affixed to the shaft 21 and projecting outwardly therefrom is an arm 23 having the outer end thereof equipped with a balance weight 24. Also secured to the shaft 110

21 is one end of an arm 25 and the remaining end of the arm 25 is connected through the medium of a link 26 with a substantially vertical lever 27 fulcrumed at its upper end 5 as at 28 upon a bracket carried by the adjacent wall of the hopper 1. The outer end of the arm 17 is connected through the medium of a link 29 with the lever 27 at a point below the link 26, while the lower end 16 of the lever 27 is formed with a handle 30.

In the modified form of the invention shown in Fig. 6, I have shown the guard 5 as formed to fit over the top of a car having the upper end thereof closed by means 15 of a cover formed centrally with an opening, the hood 5 in the modified construction being formed to completely close the loading of the latter.

In practice, the cars to be loaded are 20 moved beneath the respective loaders and the lever 30 of each loader swung from the dotted line position in Fig. 1 to the full line position and in this movement of the lever 27 the valve 16 is opened through the medium of the link 29 and arm 17, while the shaft 21 is rotated through the medium of the link 26 and the arm 25, thereby swinging the arms 20 downwardly to transmit a similar motion to the guard 5 through 25 the medium of the links 19 and in the downward movement of the guard 5 such guard engages the upper edges of the walls of the car to close the top of the car. In the downward movement of the guard 5, the pipe section 9 slides relatively to the outlet pipe 10 and the rod 14 swings the arm 13 to open the damper 12 so that the dust rising during 30 the loading of the car may be carried through the pipes 9 and 10 into the spout 11 and this dust may be delivered by the flue 11 to any suitable receiver. After the car has been loaded, the lever 27 is swung in the 35 opposite direction, thereby closing the valve 16, elevating the guard 5 and closing the damper 12, the balance weight 24 on the outer end of the arm 23 assisting in the elevating of the guard 5.

The hoppers of the loaders may be arranged 40 in such manner as to communicate with the calcine furnaces, while the flue 11 may return the dust from the calcine back to the furnaces.

While I have herein shown and described 45 certain preferred forms of my invention by way of illustration, I wish it to be understood that I do not limit or confine myself to the precise details of construction herein described and delineated, as modification and variation may be made within the scope

of the claims and without departing from 60 the spirit of the invention.

I claim:

1. In loading apparatus of the class described, a hopper, a dust guard mounted in the lower end of the hopper and capable of 65 vertical movement to cover and uncover the car being loaded, a valve movable across the lower end of the hopper to open and close the same, means for operating said valve and moving said dust guard simultaneously, 70 an outlet flue connected to said dust guard for conveying the dust away from the vicinity of the loader, a damper in said flue capable of movement to open and closed positions, and a connection between said 75 damper and dust guard whereby the damper will be operated to open position in the downward movement of the guard and to closed position in the upward movement of the guard. 80

2. In loading apparatus for calcine and other powdered material, a hopper, a dust guard connected to the lower end of the hopper and adapted for movement relatively to the hopper to cover and uncover the car 85 being loaded, a flue connected to said dust guard to convey the dust away from the vicinity of the loader, a damper in said flue, and a connection between said damper and dust guard whereby the damper will be 90 opened in the movement of the guard to cover the car, and closed in the movement of the guard to uncover the car. 95

3. In loading apparatus for calcine and other powdered material, a hopper, a dust 95 guard connected to the lower end of the hopper and adapted for movement relatively to the hopper to cover and uncover the car being loaded, a flue connected to said dust guard to convey the dust away from the 100 vicinity of the loader, a damper in said flue, a connection between said damper and dust guard whereby the damper will be opened in the movement of the guard to cover the car, and closed in the movement 105 of the guard to uncover the car, a valve controlling the flow of material from the hopper, a lever capable of swinging movement, a connection between said lever and valve, and connections between said lever 110 and dust guard whereby said dust guard and valve may be operated simultaneously.

In testimony whereof I affix my signature in presence of two witnesses.

CLAUDE H. POLK.
